L. W. LANGDON, OF NORTHAMPTON, ASSIGNOR TO HIMSELF AND
J. G. CLARK, OF SPRINGFIELD, MASSACHUSETTS.

Letters Patent No. 91,139, dated June 8, 1869.

IMPROVEMENT IN PERMUTATION-LOCKS.

The Schedule referred to in these Letters Patent and making part of the same.

To all whom it may concern:

Be it known that I, L. W. LANGDON, of Northampton, in the county of Hampshire, and Commonwealth of Massachusetts, have invented a new and improved Permutation-Lock; and I do hereby declare that the following is a full, clear, and exact description thereof, reference being had to the accompanying drawings, making a part of this specification, and to the letters of reference marked thereon, in which—

Figure 1 is a perspective view of said lock.

Figure 2 is a longitudinal sectional view, the plane of vertical section being indicated by the line X X in fig. 4.

Figure 3 is a side elevation of the same, the side of the lock being represented as broken away, to show the works.

Figure 4 is a reverse plan view of said lock, the inside plate being removed.

Figure 5 is a sectional view of one of the friction-springs, through the line y y in fig. 4.

Figure 6 is a plan view of the perforated dial, which is keyed to the main shaft.

Figure 7, I, II, III, shows two end elevations and a side elevation of the middle one of the three ferrules or sleeves which turn around the stem of the bolt.

Figure 8, I, II, III, shows two end elevations of the ferrule or sleeve nearest the bolt-end of the lock, and also an axial section through the line x x in fig. 8, I.

Figure 9 is an end elevation of the ferrule which is nearest to the main shaft.

Figure 10, I, II, shows a plan view and side view of a serrated friction-washer, which is placed between the base of the lock and the driving-gear, to hold the latter in any position to which it may be adjusted.

My invention relates to that class of locks in which the bolt is moved in and out by some means independent of the proper locking-mechanism, which latter is operated by a graduated, revolving knob, index, or dial, the movement of which is governed by a certain adjustment, according to numbers which are known to the operator, which adjustment may be changed from time to time.

The design of my invention is to construct a lock which possesses all the security of the delicate and complicated permutation-locks heretofore used, and, at the same time, consists of the smallest possible number of parts, and is both cheap and durable in its construction.

In the lock shown, the several parts are: the body or case; a bolt having a round stem, and three short studs projecting from it in a line with one another; three slotted and channelled ferrules or sleeves, which encircle the stem of the bolt; two small bevelled gears; a main driving-shaft or spindle; and the graduated

knob which turns it; a thin perforated dial keyed to the spindle; and three friction-springs and screws for holding the parts in place, with a small independent knob for shoving the bolt in and out.

The nature of my invention can be best understood from the description of its construction and operation, which is as follows:

In construction, the body or case of the lock consists of the front plate A, sides and ends A', which may be cast in one piece, and the back B which is fastened by screws, s' s'.

A cylindrical projection, a, is formed upon the face of A, through which the driving-spindle passes, and which supports the locking-knob K.

A slot, s, is also cut in the plate A, in which the stem of the small knob d moves to and fro in shoving the bolt.

The post b and buttress b' are cast with, or firmly attached to, the body of the lock, and act as guides through circular openings in which the round stem of the bolt moves back and forth, while the locking-end of the bolt passes out of the case through a rectangular opening in the end, as in ordinary locks.

The bolt E is enlarged at the locking-end into the rectangular portion e, which enters the usual bolt-socket in the door-frame, and is proportioned in size to the strain which is to be put upon the lock.

The remainder of the bolt consists of the cylindrical stem e', which is smoothly finished, and in which are firmly set the three studs c c' c'', the heads of which are rectangular, and project but a short distance above the surface of the stem e'.

The small rod which carries the knob d is firmly screwed into the bolt, and serves to shove it out into the locking-position, or to withdraw it, when the locking-mechanism has freed it.

The three ferrules, or sleeves, F F' F'', are of the same diameter and thickness, being made to fit the smooth stem e' of the bolt, about which they move as around an axle, and it is by the rotation of these ferrules that the bolt is locked, or prevented from moving back, when pushed out by the knob d into the locking-position. All these ferrules move freely about the bolt, and one is made to turn the next, and so on, by small dogs or projections on the adjacent ends of each, which engage with one another, like the teeth of gear-wheels, so that a dog is formed at each end of the middle ferrule F', while only a single dog is required upon each of the others.

The ferrule F'' is moved by the bevelled gear G, of which it forms the hub, and if it be turned until its dog, f'', comes in contact with the dog f' upon the middle ferrule, the latter will take the same rotation, and when the dog f'', at its other end, meets the dog f upon the ferrule F' the three ferrules will all move

together, and may thus be all rotated to the right or left, according to the direction of the motion of the bevelled gear G.

To allow this rotation over the projecting studs in the bolt, an annular channel is cut in the inside of each ferrule, at one end, which is deep enough to receive the stud, and allow a free rotation of the ferrules.

In order that the bolt may be drawn back through the ferrules, without the studs striking the ferrules, a longitudinal channel or groove, of the same depth as the annular grooves, is cut in the inside of the ferrules F and F', and a longitudinal slot is also cut in the third ferrule F'', so that, when these longitudinal channels, and the slot in F'', are all in the proper line with the studs on the bolt, as in figs. 2 and 4, the bolt can be readily shoved back, and the device is then unlocked.

It will be seen that if a single one of the ferrules is moved either way, so that its channel or slot is not in line with the others, the bolt cannot be drawn back.

The operation of unlocking, therefore, consists of bringing these ferrules into such positions, relatively to the bolt and to one another, that the channels for the studs are in a right line with one another, and that this right line shall coincide with the line of the studs.

It will also be seen that the action of the dogs upon the ends of the ferrules is such that, to bring all the channels in line, there must be three operations, as follows:

If the dogs are all engaged, so that the ferrules are following one another, and are moving from right to left, then this rotation will be kept up until the ferrule F is in the unlocking position; then the bevel-gear and driving-ferrule F' will be rotated in the opposite direction until the ferrule F'' is brought into unlocking-position also, when the driving-ferrule F'' is again rotated from right to left, until that also falls into the same position as the other two, when the bolt can be drawn back. If the first rotation is from left to right the result will be the same, merely reversing the direction of the three motions.

The dogs are purposely arranged so that a continuous rotation of all the ferrules in one direction cannot possibly bring all the channels in the proper line.

To prevent the ferrules F and F' from turning out of place when once adjusted, a friction-spring, g, fig. 5, is placed beneath each one, being made to exert just enough pressure to prevent loose motion, without interfering with the operation of the lock.

The die-spindle H passes down through the cylindrical projection a upon the plate A, and has the bevelled gear G keyed to its inner end, which gear meshes with the similar bevelled gear G, upon the ferrule F'', and thus transmits the motion of the driving-spindle to the system of ferrules.

A thin serrated disk, L, fig. 10, is placed behind the gear G' and is made slightly concave, to act as a presser or friction-spring.

A circular recess, h h, is formed in the top of the projection a, and receives the circular index-plate M, fig. 6, around the outer edge of which is a regular series of small round openings, which are numbered from the first, upward in order; the figures of graduation being plainly stamped in the face of the dial, which latter has an opening, l, to receive the driving-spindle, and a small slot cut in one side of the opening, which receives a small feather or key on the side of the spindle, so that the spindle and dial move together.

The base of the hollow knob K is of the same diameter as the projection a, upon which it turns, being held to place by the set-screw k, which is screwed into the end of the spindle, which extends nearly through the knob.

A small, round pin, o, projects from the inner face of K, and is made to enter one or another of the

series of holes in the dial-plate M, and when thus entered and held in place by turning in the screw k, the knob, dial, and spindle will all move together, and the ferrules may be rotated by turning the knob.

Around the base of the knob K is a scale, plainly graduated, and extending, in the lock shown, from one to forty-eight inclusive, the lines of graduation being carried to the edge of the knob, so as to bring the line corresponding to any figure in a right line with the starting-point, which is made on the projection a.

One or more of the starting-points may be made at different points in the periphery of a, and suitably distinguished by marks, thus further complicating the facts which it is necessary for the operator to know in opening the lock.

When the lock, thus constructed, is to be used, the object of the operator is to find out the three numerical adjustments of the knob K, which will enable him to bring all the ferrules into the position shown in fig. 4, so that the bolt can be drawn back.

To make this easier to be seen, short slots are cut in the ends of the ferrules, so that the studs upon the bolt can be seen when the ferrules are properly turned; but, instead of the slots, a line might be made along each ferrule over the middle of the longitudinal channel beneath, and a point or line upon the post b, with which the lines upon the ferrules should be made to range when they are brought into the unlocking-position.

The back plate B being removed, the operation of finding the adjustment is as follows, the pin o in the knob being supposed to be in the hole marked 1 in the dial:

The knob is turned in the direction of the arrow, once or twice around, or until the dogs on the ferrules are all brought in train, and the ferrules following one another, which following the operator will generally feel from the knob, and must occur in two or three revolutions.

The zero-point, which is numbered 48 in the lock shown, is then brought round to the starting-point on the projection a, and the knob is then turned in the direction of the arrow until the operator sees that the ferrule F is in the unlocking position, when he notes what number on the knob is opposite the starting-point, and in this case finds it to be 21 $\frac{1}{2}$. He then turns the knob in the opposite direction until the middle ferrule F' is brought to the same position, and again notes the number on the knob against the starting-point, which will be 14, and, finally, he again turns the knob in the direction of the arrow until the last ferrule is turned into the unlocking-position, and finds his third number to be 37.

If the operator should, however, begin by rotating the knob in a direction opposite to the direction of the arrow, to obtain the first number, then in the direction of the arrow for the second, and so on, the adjusting-numbers will be found to be 31 $\frac{1}{2}$, 10, 37.

To unlock, therefore, the operator has only to be in possession of either of these sets of numbers, 21 $\frac{1}{2}$, 14, 37, or 31 $\frac{1}{2}$, 10, 37, with the further knowledge of whether the knob is to be first turned with the arrow or opposite to it.

If it should become desirable to change the adjustment of the lock, for purposes of safety, the set-screw k can be turned out, and the knob K turned so that the pin o shall fill some other hole in the dial, when new numbers will be found, to follow the adjustment of the ferrules; as, for instance, if the pin o be set in the fifth hole in the dial, the adjustment following the arrow will be found to be 14, 7, 30; or, in the reverse direction, 13 $\frac{1}{2}$, 2, 10, and so on, for every hole in the dial.

The numbering of the holes in the dial is intended mainly as a safeguard, so that if the knob be mischievously turned, so that the pin o is entered in some other hole, the owner of the lock can immediately restore

the knob to its proper place. It is therefore necessary that the owner of the lock should retain in mind, or on record, the number of the hole in the dial in which the pin o was placed when the numerical adjustment was obtained for use.

The knob and dial may also be removed from the lock, if desirable, leaving still less means for tampering with the lock.

By varying the position of a single dog on one ferrule the numerical adjustment of two locks, which are otherwise perfect duplicates, will be entirely different, and a like variation will follow a relative change in the number of teeth on one or other of the bevelled gears.

If the lock is to be used upon a house-door, an inside knob, dial, spindle, and bevelled gear, may be applied directly opposite the outside one shown, and having the same operation.

Any number of ferrules, greater than one, may be used, each ferrule adding a new number to the numerical adjustment; and all the ferrules may be enclosed in a single sleeve, in which small holes, like oil-holes, may be made, answering to certain holes in the ferrules, when the latter are brought to place, in which case a pointed wire would be used for ascertaining when the ferrules were in unlocking-position.

The studs upon the stem of the bolt need not be placed in a right line; but the arrangement shown is more convenient than an irregular location of the studs, and equally safe.

I am aware that slots may be cut in all the ferrules in place of the longitudinal channels, and consider the

same an equivalent for such channels, but prefer the latter, as leaving the ferrule more rigid and durable.

I do not claim broadly a series of channelled and revolving ferrules, arranged on a bolt, having studs set therein, as I am aware that such have been used; neither do I claim rotating one ferrule from another by means of projections on the adjacent ends thereof; but having described my invention,

What I claim as new therein, and desire to secure by Letters Patent, is—

1. In combination with the locking-bolt of a permutation-lock, having studs set on the cylindrical part thereof, a series of revolving ferrules, having annular and longitudinal channels and dogs upon the adjacent ends thereof, when said ferrules revolve on the locking-bolt, are arranged and enclosed within a casing, and are operated by means of power applied to one of the ferrules, substantially as herein described.

2. The combination and arrangement of the bolt E, having projecting studs, the series of channelled and revolving ferrules F, with projecting dogs f at the adjacent ends thereof, bevelled gears G G', driving-spindle H, dial M, and graduated knob K, having a projecting pin, o, the whole applied to the lock-body, and operating substantially as described.

In testimony whereof, I hereunto set my hand, this 23d day of June, A. D. 1868.

L. W. LANGDON.
